Ladislav Dugovic, INVENTOR
BY Victor J. Evans

HIS ATTORNEY

WITNESS:

UNITED STATES PATENT OFFICE

LADISLAR DUGOVIC, OF CHICAGO, ILLINOIS

WINDOW LATCH

Application filed April 21, 1928. Serial No. 271,938.

This invention relates to certain novel improvements in window latches and has for its principal object the provision of an improved construction of this character which will be highly efficient in use and economical in manufacture.

Among the objects of my invention is to provide a device which may be used to latch windows and similar devices which will be arranged such that it may be moved from operative position when such a movement is desirable.

Another object of the invention is to arrange a device of the foregoing character such that the latched members may be moved a predetermined distance.

Another object of the invention is to arrange a device of the foregoing character in such a manner that it will be arranged such that the parts will be disposed in a position which will be readily visible so as to indicate the condition of the latch.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a top plan view of a preferred embodiment of my invention associated with a window construction which is fragmentarily shown;

Fig. 2 is a sectional view taken substantially on the line 2—2 on Fig. 1;

Fig. 3 is a sectional view taken substantially on the line 3—3 on Fig. 1;

Figs. 4 and 5 are sectional detail views depicting the embodiment of my invention illustrated herein in two of its operative positions.

In the drawings, wherein the preferred embodiment of my invention is illustrated, 10 indicates the lower sash of a window construction and 11 indicates the upper sash thereof and these sashes are arranged for sliding movement in vertical planes and are disposed out of alignment with each other, 50 the lower sash being disposed inwardly to-

ward the room as is well understood in the art.

My improved latching device includes a main body member 12 which terminates at one end in a tongue portion 13 that includes ears 14. A leaf 15, which has an ear 16 adapted to be disposed between the ears 14, is provided and a pintle 17 extends through suitable openings in these ears so as to hingedly connect the main body portion 12 to the leaf 15. The upper edge of the upper frame of the sash 10 embodies a recess 18 into which the leaf 15 is fitted and which is secured therein in any approved manner as by the wood screws 19. The main body portion 10 is arranged to include a housing 20 which is preferably hollow and the housing 20 includes a wall 21 which is adapted to terminate in engagement with the upper edge of the lower frame member of the sash 11 as is clearly indicated in Fig. 2 and therefore the end of the wall 21 and the bottom edge of the portion 13 will be disposed in alignment when the sash frames are aligned as is understood in the art.

Mounted on the upper edge of the lower frame member of the sash 11 is a clamp member 22 which is secured to said frame member in any approved manner as by the wood screws 23. The member 22 includes an upwardly protruding portion 24 which has ears 25 provided on the upper edge thereof. The clamping member 22 is adapted to be disposed within the housing 20 as is best illustrated in Figs. 2 and 3. Extending across the housing 20 transversely to the portion 13 is a slot 25 and as is best illustrated in Fig. 3, the portion of the slot disposed in the wall 26 of the housing 20 is closed by a portion 27. In substantially the mid-point of the portion of the slot 25 arranged in the upper wall 28 of the housing 20, the slot 25 is enlarged as indicated at 29 so as to provide a substantially circular opening. It is apparent that the slot 25 extends across the housing and divides said housing into two sections, save for the portion 27 which serves to interconnect these two sections of the housing.

Pivotal secured to the ears 25 is the reduced portion 30 of the substantially cylindrical rod 31, said reduced portion defining

shoulders 32 on said rod. Adjacent the shoulders 32 and adapted to extend into the reduced portion 30 is a recess 33, the utility of which will be made apparent presently. On the upper side 28 of the housing 20, an arm 34 is pivotally mounted on one side of the slot 25 and on the opposite side of the slot 25 on the side 28, a lug 35 is mounted which is arranged so as to retain the pivotally mounted arm 34 when it is disposed across said slot 25.

After the device has been mounted in the manner hereinbefore described, the arm 31 is disposed so that the reduced portion 30 thereof will be arranged in the portion 36 of the slot 25 and the arm 34 is disposed so as to be out of position above the slot 25, a pin 37 being provided on the upper side 28 to limit this retracting movement of the arm 34. It is apparent that with the parts in the just described position, the sashes 10 and 11 may be moved relative to each other since the portion 30 of the arm 31 will move through the portion 36 of the slot 25. However, when the portion 30 of the rod 31 is moved over into engaging relation with the portion 27 into the position depicted in Fig. 3 any relative movement by the sashes 10 and 11 will tend to move the housing 20 relative to the member 22 and thus the portion 27 will act on the arm 31 to tend to move said arm upwardly which will move the shoulders 32 thereof into engagement with the outer edge of the wall 26 which will securely latch the sashes 10 and 11 so as to prevent further relative movement therebetween. It will thus be seen that this device may expeditiously be used so as to serve as a latch for the window. The portion 27 will rest in the recess 33 in order that the arm 31 will be disposed substantially horizontal. The device also embodies another utility which will now be set forth.

When the arm 31 is disposed in the position depicted in Fig. 3 the arm 34 is moved across the slot 25 into a position such that it will be retained by the lug 35. The arm 31 may then be moved to a substantially vertical position and it will therefore be disposed in engagement with the arm 34. However, should the sashes be moved relative to each other the arm 31 will ride in the substantially cylindrical opening 29. It is therefore apparent that the sashes may be moved relative to each other and that the rod 31 will slide along in this opening 29. In order to limit this relative movement, the rod 31 is made of a predetermined length and a ball 38 is provided on the upper end of this rod which is of greater size than the opening 29 and it is therefore apparent that when the ball 38 engages the wall 28, further movement between the sashes will be prevented. Figs. 4 and 5 serve to clearly depict this relative movement, Fig. 5 depicting the greatest movement possible between the sashes 10 and 11 and showing the rod 31 in substantially vertical position. Fig.

4 shows the sashes 10 and 11 in the position occupied at the start of the movement and this view also substantially depicts the approximate amount of relative movement between the sashes which is necessary to bring the shoulders 32 into the hereinbefore mentioned engaging position which serves to prevent relative movement between the sashes.

When it is desired to wash the windows or otherwise move the sashes relative to each other in a great amount, the section 30 is disposed in the portion 36 of the slot 25 and the housing 20 and the portion 13 are pivoted about the pintle 17 into the position depicted in dotted lines in Fig. 2 and when in this position it is apparent that the sashes may be moved in any desired amount relative to each other and also the appurtenances will be disposed from position relative to the window panes of the sash so as to facilitate cleaning thereof.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A device of the character stated including a member including a housing, another member adapted to normally be disposed within said housing, an arm pivotally mounted on said last named member, said housing having a slot formed in the walls thereof, said arm including a reduced portion adapted to be disposed in said slot, and means on said housing adapted to support the reduced portion of said arm in a position relative to said slot such that a shoulder defined by said reduced portion will engage the wall portions of said housing adjacent said slot when said members are moved relative to each other.

2. In a device of the class described, a member including a housing, another member adapted to be normally disposed within said housing, an arm pivotally mounted on said second named member, said arm having a reduced portion adjacent the pivotal connection thereof, said housing having a slot formed in the walls thereof adapted to be closed at one end, the upper wall of said housing having an enlarged opening formed therein in communication with said slot, means for positioning said pivotally mounted arm in said slot relative to said enlarged opening, and a member formed on the end of said arm adapted to be of larger size than said enlarged opening.

3. In combination with a window construc-

tion, a member mounted on the lower sash member of said window construction including a housing adapted to extend over the lower frame member of the upper sash member, 5 a member mounted on the lower frame of said sash member adapted to be disposed within said housing at predetermined times, said housing having a slot formed therein, an arm pivotally mounted on said member mounted 10 on said upper sash having a reduced portion adapted to be disposed in said slot, means for retaining the reduced portion of said arm in said slot, said reduced portion defining a shoulder on said arm adapted to engage the 15 walls adjacent said slot whereby to prevent relative movement between said sash members.

4. In combination with the adjacent rails of a sash construction, a member pivotally 20 mounted on one of said rails including a housing adapted to be disposed over the other of said rails, a member mounted on said other of said rails adapted to be disposed within said housing at predetermined times, an arm 25 pivotally mounted on said last named member having a reduced portion adjacent the pivotal mounting thereof, said housing having a slot formed therein adapted to receive the reduced portion of said arm, a member 30 for closing one end of said slot, said arm being adapted to be normally disposed with the reduced portion thereof in said slot adjacent the closed end thereof.

5. In combination with the adjacent rails 35 of a sash construction, a member pivotally mounted on one of said rails including a housing adapted to be disposed over the other of said rails, a member mounted on said other of said rails adapted to be disposed within 40 the housing at predetermined times, an arm pivotally mounted on said last named member having a reduced portion adjacent the pivotal mounting thereof, said housing having a slot formed therein adapted to receive the reduced portion of said arm, said slot being 45 closed at one end thereof, the upper wall of said housing embodying an enlarged opening communicating with said slot, means for retaining said reduced portion of said arm 50 in said slot in alignment with said enlarged opening, and a member on the free end of said arm adapted to be of larger size than said opening.

6. In combination with the adjacent rails 55 of a sash construction, a member pivotally mounted on one of said rails including a housing adapted to be disposed over the other of said rails, a member mounted on said other of said rails adapted to be disposed within 60 said housing at predetermined times, an arm pivotally mounted on said last named member having a reduced portion adjacent the pivotal mounting thereof, said housing having a slot formed therein adapted to receive 65 the reduced portion of said arm, a member

for closing one end of said slot, said arm being adapted to be normally disposed with the reduced portion thereof in said slot adjacent the closed end thereof, said arm having a recess formed therein adapted to receive said slot closing member whereby said arm will be disposed in a substantially horizontal position.

In testimony whereof I affix my signature.

LADISLAR DUGOVIC.
